UNITED STATES PATENT OFFICE.

ADAM DERRENBERGER, OF TACOMA, WASHINGTON.

GOLD-SEPARATOR.

SPECIFICATION forming part of Letters Patent No. 554,912, dated February 18, 1896.

Application filed June 3, 1895. Serial No. 551,548. (No model.)

To all whom it may concern:

Be it known that I, ADAM DERRENBERGER, a citizen of the United States, residing at Tacoma, in the county of Pierce and State of Washington, have invented certain new and useful Improvements in Gold-Separators; and I do hereby declare the following to be a full, clear, and exact description of the invention, such as will enable others skilled in the art to 10 which it appertains to make and use the same.

My invention relates to improvements in ore-separators, and has particular relation to gold-separating apparatus.

The invention consists of the combination, 15 with a main frame, of an independent laterally-shaking frame, a series of gold-retaining connected trays mounted in the same, an independent longitudinally-sliding frame mounted below the aforesaid frame, an end- 20 less amalgamating-belt mounted on said latter frame and adapted to receive the discharge from the lower of said trays, and means for operating the laterally-shaking frame and the longitudinally-sliding frame simultaneously.

25 It also consists of certain other novel constructions, combinations, and arrangements of parts, all of which will be hereinafter more particularly set forth and claimed.

In the accompanying drawings, forming 30 part of this specification, Figure 1 represents a central vertical longitudinal section through the devices embodying my invention. Fig. 2 represents a transverse vertical section, partly broken away, of said devices on the line x x 35 of Fig. 1. Fig. 3 represents a top plan view of said devices. Fig. 4 represents an end elevation of the same. Fig. 5 represents a side elevation of said devices; and Fig. 6 represents a detail top plan view, partly in section, 40 of a portion of the longitudinally-moving frame and the amalgamating apron or belt, the latter being broken away to expose the cleaning-brushes.

45 A in the drawings represents the main frame of the machine; B, the laterally-shaking frame; C, the longitudinally-sliding frame, and D the amalgamating-belt mounted on the latter. The laterally-shaking frame or box B is mounted between the uprights of 50 the frame A by flat bars b , which are pivoted at their upper ends to the cross-bars of the frame and have their respective lower ends

pivoted to the respective lower sides of the said box. It will thus be seen that said frame B is free to swing laterally from side to side, 55 the uprights of the frame A being set far enough apart to permit this swinging without said frame coming in contact with the said uprights. This frame B is open top and bottom and is provided at its top with a fixed 60 grating b' , that inclines toward the rear of the machine. Oppositely-inclined guides b^2 are mounted upon the sides of the box to receive and support the inclined riffle-trays b^3 and the inclined amalgamating-trays b^4 . The trays 65 b^3 have their bottoms provided with riffle-bars b^5 , extending laterally across the same so as to form pockets to arrest nuggets and other coarse particles of gold. The amalgamating-trays b^4 have their bottoms covered with copper plates, upon which mercury is spread, so as to catch all fine particles of gold as they pass over said plates. The lower end of the lower amalgamating-tray is provided with a lateral trap b^6 to catch small particles of quick- 70 silver that have escaped all the trays. 75

It will be seen that the sand or crushed ore containing the gold will be discharged from the lower end of the top tray onto the upper end of the oppositely-inclined tray beneath 80 the same, and so on through the entire series until the last tray is reached, when all the remaining gold, sand, &c., will be discharged upon the amalgamating-apron.

It will also be seen that each of the trays 85 can readily be removed to clean the gold from its riffles or amalgamating-plate. The trays are held firmly in position while the machine is in operation by rods b^6 , which pass through screw-eyes b^7 , attached to the ends of said 90 trays and also to frame B in such a manner that each of said rods can be passed straight through all of the eyes on its respective end of the machine.

An ore or sand feeding hopper or chute a is 95 mounted on the frame at the upper end of the grating b' so as to discharge thereon. A water-chute a' is also mounted on said frame so as to discharge upon the said upper end of the grating beneath the discharge of the chute 100 a . All large pieces of ore, stone, sticks, and the like pass down the grating and are discharged from the machine without entering the oppositely-inclined trays.

Upon one of the uprights of the frame is mounted a journal-frame, consisting of two spacing-blocks f , connected by metallic plates f' . A combined belt and gear-wheel F is journaled in this frame by its shaft f^2 , which is squared at its outer end so that a crank-operating handle can be applied thereto when so desired. The toothed portion of the wheel F engages a small gear f^3 , also journaled in said frame by its shaft f^4 , which carries a crank-disk f^5 , provided with a crank-pin f^6 . Bell-crank levers h are pivoted on the frame in a horizontal position, and have their respective inner ends connected to the frame B by links h' . The outer ends of said levers are connected by a bar h^2 , so that they must both move together. The bar h^2 is provided with an eye h^3 . A pitman h^4 has one end mounted on the crank-pin f^6 and the other passed through said eye h^3 , so that as the crank-disk is rotated the bell-crank levers are operated, and thus shake the frame B from side to side in an approximately horizontal plane.

25 A lever H is pivoted on the frame A at one end, and has its opposite end connected to the sliding frame C by a link c . A pitman c' connects said lever H and the crank-pin f^6 , and the said sliding frame is thus reciprocated when the crank-disk is rotated; but such reciprocation is at right angles to the shaking action of the frame B . The under side of said frame C is provided with metallic plates c^2 , as is also the upper surface of frame A , upon which said frame C slides, so said frame may slide with as little friction as possible, as lubricant can be introduced between said plates. The endless copper amalgamating-belt D is mounted in an inclined position 40 in said frame by rollers d d' , journaled at the front and rear ends of said frame, and supplemental rollers d^2 d^3 d^4 .

The rollers d d' d^3 are each provided about their middles with an annular groove d^5 to 45 accommodate a tension cord or rope d^6 , which passes about said rollers and assists in supporting said belt and keeping it from sagging in the middle. Longitudinal strips d^7 are mounted in said frame C to support the upper 50 edges of the said amalgamating-belt. Said belt is revolved intermittently, being moved each time the frame moves forward. This movement is caused by a lever I mounted loosely upon one of the journal ends of the 55 shaft of the roller d' and provided with a pivoted pawl i which engages a ratchet-wheel i' fast on said journal end. The outer end of said lever I is connected to the frame A by a link i^2 so that as the frame C is reciprocated 60 back and forth said lever will be rocked upon said journal end and thus cause the rotation of the said roller d' by the pawl and ratchet and thus the belt will move forward.

The forward part of the frame C is provided 65 with a combined scraper and discharge-gutter C' . The scraper portion of this part C' en-

gages the surface of the amalgamating-belt, and as the latter revolves the mercury and gold are scraped from the surface of said belt and conducted away by said gutter portion. 70

It will be seen from the foregoing that the amalgamating-belt inclines forward and downward and receives the ore, sand, water, &c., from the lower tray at its rear end and with the result that all of the ore, sand, &c., 75 will flow forward down said belt over the entire upper surface of the same and any fine gold that escaped the trays above will be caught and retained upon the amalgamated surface of said belt. To get the best results 80 from the belt it must be kept bright and clean and be freshly amalgamated each time it makes a complete revolution, as the mercury is scraped from the same by the scraper C' as the belt moves around. For this purpose I 85 provide the frame C with guides c^3 , in which are mounted a sliding brush and a sliding polisher c^4 c^5 , respectively. Both the brush and the polisher bear against the outer surface of the belt and are reciprocated laterally 90 beneath the same by bell-crank levers c^6 c^7 pivoted on the respective sides of the frame C and connected to said brush and polisher, respectively, by connecting-rods c^8 . The outer ends of each of the said bell-crank levers are 95 connected to the frame A by connecting-rods c^9 . The result of this construction is that as the frame C is reciprocated back and forth the bell-crank levers which are connected to the stationary frame must be operated and 100 thus reciprocate the brush and polisher.

An amalgamating-tray K is arranged below the belt D , and the roller d^3 is so placed that said belt D must pass through the mercury in said tray as it revolves and thus become 105 thoroughly amalgamated.

My machine is designed particularly for the working of "floating gold," or such gold as is contained in the sand taken from river-beds and the like; but crushed ore can be worked 110 equally well if so desired.

My machine can either be operated by hand by attaching a suitable crank-handle to the squared end of the shaft f^2 or by any suitable power-belt passed about the belt-wheel F . 115

Having now described my invention, what I claim as new, and desire to secure by Letters Patent, is—

1. In a gold-separator, the combination with a main frame of an independent laterally-shaking frame, a series of gold-retaining connected trays mounted in the same, an independent longitudinally-sliding frame mounted below the aforesaid frame, an endless amalgamating-belt mounted on said latter frame and adapted to receive the discharge from the lower of said trays, means connecting the power-shaft with both the laterally-shaking and longitudinally-sliding frames whereby they are reciprocated simultaneously, and means for rotating said belt simultaneously with the reciprocation of the frames, all of 120 125 130

said parts being constructed and arranged to be set in motion by the same power-shaft, substantially as described.

2. In a gold-separator, the combination with 5 a main frame, of an independent laterally-shaking frame, a series of gold-retaining trays mounted in the same and discharging one into the other, a longitudinally-sliding frame below the laterally-shaking frame, a rotary amalgamating-belt mounted upon the same and adapted to receive upon its upper surface the discharge from the lower one of said trays, and means for operating said laterally-shaking frame and longitudinally-sliding frame 15 simultaneously, and means for operating the amalgamating-belt, comprising a vibrating lever pivoted on the axle of one of the belt-supporting drums and connected with the main frame, a pawl on said lever, and a ratchet-wheel on said axle, substantially as 20 described.

3. In a gold-separator, the combination with a main frame, of an independent laterally-shaking frame, amalgamating-trays mounted 25 in the same, a longitudinally-sliding frame below said laterally-shaking frame, an endless rotary amalgamating-belt mounted on said latter frame, and means for operating said frames simultaneously; said means comprising 30 a power-shaft, horizontally-arranged bell-crank levers mounted on the main frame and connected to the laterally-shaking frame and the power-shaft, and an operating-lever also mounted on the main frame and connected to 35 the power-shaft and the longitudinally-sliding frame, substantially as described.

4. In a gold-separator, the combination with a main frame, of an independent laterally-shaking frame, gold-retaining trays mounted 40 in the same and communicating with each other, a longitudinally-sliding frame, a rotary amalgamating-belt mounted upon the same and below said trays and adapted to receive upon its upper surface the discharge from the

said trays, a scraper and discharge-trough 45 for removing the mercury and gold from said belt, polishing-brushes for said belt, a mercury-tray through which said belt passes, and means for operating said laterally-shaking frame and the amalgamating-belt simultaneously from the same power-shaft, substantially as described.

5. In a gold-separator, the combination with a main frame, of an independent laterally-shaking frame, oppositely-inclined riffle and 55 amalgamating trays mounted in the same and communicating with each other, an independent sliding frame mounted below said shaking-frame, a rotary amalgamating-belt mounted on said sliding frame, and reciprocating brushing and polishing devices mounted below said belt and engaging the same, and amalgamating mercury-tray through which said belt passes, and means for operating the laterally-shaking frame and the longitudinally-sliding 60 frame, substantially as described.

6. In a gold-separator, the combination with a main frame provided with a feeding-hopper, an independent shaking-frame, removable oppositely-inclined riffle and amalgamating 70 trays, an independent sliding frame below said shaking-frame an endless inclined amalgamating-belt mounted on said frame so as to receive upon its upper surface the discharge from the lower of said trays, means for intermittently revolving said belt, a scraper for removing the mercury and gold from said belt, reciprocating, cleaning and polishing devices 75 engaging said belt, a mercury-tray through which said belt passes, and means for operating the shaking-frame, substantially as described.

In testimony whereof I hereunto affix my signature in presence of two witnesses.
